UNITED STATES PATENT OFFICE.

ARTHUR W. CLARK, OF CONSHOHOCKEN, PENNSYLVANIA, ASSIGNOR TO JOHNSON & JOHNSON, OF NEW BRUNSWICK, NEW JERSEY, A CORPORATION OF NEW JERSEY.

MANUFACTURE OF SURGICAL LIGATURES.

No. 923,768.

Specification of Letters Patent.

Patented June 1, 1908.

Application filed May 3, 1906. Serial No. 315,105.

To all whom it may concern:

Be it known that I, ARTHUR W. CLARK, a citizen of the United States of America, residing in Conshohocken, in the county of 5 Montgomery, in the State of Pennsylvania, have invented certain new and useful Improvements in the Manufacture of Surgical Ligatures, of which the following is a specification.

10 The main object of my invention is to so treat the material for surgical ligatures made of animal tissues (ordinarily termed "catgut", with an antiseptic or germicide, that the antiseptic or germicidal qualities of the 15 ligatures thus treated will be more lasting and effective. This object I attain by charging the ligature strands while in an open, unbraided or untwisted state with an antiseptic, and then twisting the strands so as to thereby 20 mechanically grasp the antiseptic and hold it.

The common method of rendering ligatures antiseptic is to impregnate the twisted ligature with carbolic acid, mercury bichlorid, or other antiseptic solution. By this 25 method the process of impregnation is very difficult, the layers of twisted strands preventing the antiseptic or germicidal substance reaching all portions of the ligature 30 fibers or tissues. In such cases the antiseptic or germicide must be a soluble one, the antiseptic being dissolved in the solvent and the twisted or spun ligature dipped into the solution. This process fails to accomplish 35 the desired result, and moreover, in such process the use of an insoluble substance is entirely precluded.

I accomplish the desired result in the following manner: In the case of a soluble antiseptic or germicide, the substance is dissolved in a suitable solvent and the untwisted or unbraided strands are impregnated with the solution, leaving every part of the ligature thoroughly and uniformly charged. 45 The ligature is then twisted or braided in the usual manner.

In using an insoluble antiseptic or germicide, I make a fluid mixture of the substance which is to be used as the antiseptic, and I 50 thus mechanically suspend the substance in the fluid. I take the strands of "catgut" while in a loose or free state, that is, more or less untwisted or unbraided, and I dip these free strands into the mixture, so that when 55 they are taken out, their surfaces will be

found coated or charged with the undissolved antiseptic. The strands thus coated are then twisted into a string or cord so that the particles of antiseptic or germicide may be thereby mechanically grasped and held by 60 the strands thus twisted. It will be understood that I use the expression "twist" in a sufficiently general sense to apply to spinning and braiding, as well as ordinary twisting of the strand or strands, to thereby produce the mechanical grip on the salt particles. I also use the term "ligatures" in a sufficiently general sense to include "sutures".

While I do not wish to limit myself to the 70 use of any particular insoluble antiseptic or germicide, I have found that iodid of silver is well adapted for the purpose.

The advantage resulting from the use of 75 an insoluble salt as an antiseptic, as compared with a soluble antiseptic, is the lasting quality of the insoluble salt, which is not absorbed away from the ligature in use, but lasts practically as long as the ligature remains in the tissue unabsorbed.

80 The new ligature or suture herein described forms the subject of a separate patent No. 861,231, granted July 23, 1907.

In this specification I use the term "insoluble" to mean that the antiseptic is insoluble 85 in water, alcohol, ether or the ordinary solvents which are acceptable and practicable, so that a solution of the antiseptic cannot be made with which to impregnate the ligature in the ordinary manner. On the other 90 hand, when a ligature charged with an insoluble antiseptic in the manner I have described is embedded within the living tissue, the vital processes which take place cause 95 disintegration of the ligature and the antiseptic is taken up or absorbed by the organisms present or by the living tissue, in a way which is not fully understood, but which doubtless implies a slow dissolving of the antiseptic.

100 I claim as my invention—

1. The process herein described of preparing surgical ligatures of animal tissue, consisting in coating or charging the strands for the ligatures with an insoluble antiseptic 105 substance while the ligatures are in a loose state, and thereupon mechanically grasping and holding the antiseptic substance to the strands by twisting the latter.

2. The process herein described of preparing

ing surgical ligatures of animal tissue, consisting in mechanically suspending an insoluble antiseptic in liquid, dipping the strands for the ligatures while in a loose state into this mixture, thereupon mechanically grasping and securing the particles of the antiseptic substance to the strands by twisting the latter.

In testimony whereof I have signed my name to this specification, in the presence of 10 two subscribing witnesses.

ARTHUR W. CLARK.
